United States Patent Office

Des. 225,847
Patented Jan. 9, 1973

225,847

PISTOL

Philip R. Lichtman, 35 Lee St., Cambridge, Mass. 02139

Filed Feb. 23, 1971, Ser. No. 118,210

Term of patent 14 years

Int. Cl. D22—01

U.S. Cl. D22—1

Fig. 1.

Fig. 2.

Fig. 3.

Fig. 4.

Fig. 5.

Fig. 6.

FIG. 1 is a top plan view of a pistol showing my new design.

FIG. 2 is a left side elevational view thereof.

FIG. 3 is a bottom plan view thereof.

FIG. 4 is a front elevational view thereof.

FIG. 5 is a rear elevational view thereof.

FIG. 6 is a right side elevational view thereof.

I claim:

The ornamental design for a pistol, substantially as shown and described.
